UNITED STATES PATENT OFFICE.

WILLIAM B. WHITE, OF QUINCY, MASSACHUSETTS.

MANUFACTURE OF CASES FOR EYEGLASSES.

SPECIFICATION forming part of Letters Patent No. 363,267, dated May 17, 1887.

Application filed May 10, 1886. Serial No. 201,760. (No model.)

To all whom it may concern:

Be it known that I, WILLIAM B. WHITE, of Quincy, in the county of Norfolk and State of Massachusetts, a citizen of the United States 5 of America, have invented a new and useful Improvement in the Manufacture of Cases for Eyeglasses, of which the following is a specification.

This invention relates to the manufacture of 10 cases for eyeglasses, &c., such as are described and shown in Letters Patent of the United States dated March 21, 1876, No. 175,171; and the invention consists, in substance, first in placing two pieces of suitable material—such 15 as leather, &c., previously cut to the desired size and shape for the sides of the case—evenly together and between suitable clamps, then placing a metallic frame, which has previously been folded longitudinally and bent substantially into the proper shape, over the edges of 20 the said sides, and then in a suitable press pressing and firmly binding the metallic frame closely down upon the edges of the sides, completing the case, which, removed from the press, 25 is ready for use, all substantially as hereinafter fully described, reference being had to the accompanying plate of drawings, in which is shown apparatus for carrying out this invention.

30 Figure 1 is a perspective view of a press substantially constructed and arranged for binding the metallic frame upon the sides of the case. Fig. 2 is a perspective view of a receptacle in which the sides are placed preparatory to 35 clamping them together; Fig. 3, a partial side and partial longitudinal sectional view of the clamp and the receptacle in longitudinal section, with the two sides of a case therein in longitudinal section and clamped together. Figs. 40 4 and 5 are vertical cross and longitudinal sections, respectively, on lines 4 4 5 5, Fig. 1, with a case placed therein ready for operation thereon, and also in section. Fig. 6 is a plan view of Fig. 3. Fig. 7 is a detail plan view, 45 to be hereinafter referred to; Fig. 8, a perspective view of a case all complete.

In the drawings, A represents a block or plate 50 having a rib or raised portion, B, extending along three sides in the outline shown in Figs. 2 and 6, the inner walls, C, of the portion B corresponding in shape and size to the shape

of the spectacle-case desired, and for the edges f of the sides of the case, before the metallic frame is secured thereto, to just fit in the space between the walls C.

E is the clamp, which is formed of two parts or arms, a b, hinged together at d, having handles F; and secured to the end of each arm a b, respectively, is a thin plate, G H, of metal, each of which plates corresponds to the shape 60 and outline of the sides for the case, but is a little smaller all round, as shown in Fig. 6 more particularly, in order to leave the edges f of the sides free for the securing of the metal frame thereon. The plate G is rigidly secured 65 to its arm b and the plate H to its arm a by a pivot, g, on an offset, h, at its central portion, so that when the sides are placed between the two plates and the plates closed upon them they will be held firmly and closely together 70 at all points except at their edges, as before described. The two plates G H are of equal size and attached to their respective arms so as to be exactly opposite each other.

J is a press for pressing the metallic frame 75 to and upon the edges of the side pieces, and is formed of two parts, K L, one of which, K, rests upon springs l, which rest upon the flanges m of the lower portion, L, each of which springs encircles a bolt, M, screwing into the flanges m 80 and passing freely through openings n in the part K, whereby the part K can be freely moved up and down and be guided in such movements by the bolts M, the heads p of the bolts limiting its upward movement.

The upper part, K, overlaps a portion, N, of 85 the lower part, by which it is also guided, and each has a narrow shoulder, r s, which shoulders conform to the shape and size of the case when finished. The two pieces t u, forming 90 the sides of the case, having first been cut to the required shape and size and placed together, their face sides outward, are placed in the receptacle A, close against the end portion, v, of the rib B, which brings the two pieces 95 evenly together. The two plates G H of the clamp E are then opened from each other by operating their handles, and preferably the one, G, placed under the side pieces, t u, and between them and the bottom w of the receptacle 100 A, and pushed up as far as it will go, its movements being limited and regulated by the cross-

projecting pin *x* on the arm *b* abutting against the end of the receptacle.

P is a central longitudinal opening or recess in the bottom of the receptacle, to allow for the insertion of the arm *b* of the clamp. The clamping-plates are then closed upon the side pieces by operating the handles, and then the metallic frame or strip *Q*, which is first folded longitudinally and bent substantially into the form desired for the case *R*, is then placed over the edges *f* of the two side pieces, as shown in Fig. 7, and the ends *b'* then brought toward each other and onto the edge pieces of the sides and there held. The whole is then slid end-
wise into the press *J*, between the shoulders *r* and the walls *d'*, as far as it will go, and then the upper part, *K*, of the press is moved down upon the lower part in any suitable manner, which presses the metallic strip or frame between the two shoulders *r* and causes it to be firmly bound and pressed upon the edges of the case. When raising the part *K*, the case can be removed from the press and used as desired.

It is preferable to have the shoulders *r* at their outer edges, *f'*, approach each other a little to more firmly press or nip the edges *g'* of the metallic strip *Q* onto the material of which the side pieces are made.

By this process the sides of the case are

evenly placed together and there held, and the metallic frame placed around their edges and firmly secured thereto, all in a simple, quick, convenient, practical, and quite inexpensive manner.

This invention is applicable to other forms of cases for eyeglasses, &c., than the one herein shown, as is obvious.

Having thus described my invention, what I claim is—

That improvement in the manufacture of cases for eyeglasses, spectacles, &c., composed of two sides of a suitable material and a metallic edge frame, consisting of first placing the two sides of the case evenly together at their edges, then clamping them together at their central portions, and when so clamped placing the metallic frame folded longitudinally around the edges of the sides and one end, and then pressing and binding the metallic frame upon said edges, substantially as described.

In testimony whereof I have hereunto set my hand in the presence of two subscribing witnesses.

WM. B. WHITE.
